UNITED STATES PATENT OFFICE.

EDMUND VICTORY, OF WATERTOWN, NEW YORK, ASSIGNOR OF ONE-HALF
TO CHARLES R. REMINGTON, OF SAME PLACE.

PULP-SCREENING MACHINE.

SPECIFICATION forming part of Letters Patent No. 417,451, dated December 17, 1889.

Application filed April 19, 1889. Serial No. 307,895. (No model.)

To all whom it may concern.

Be it known that I, EDMUND VICTORY, of Watertown, in the county of Jefferson and State of New York, have invented a new and useful Improvement in Pulp-Screening Machines, of which the following is a specification.

My invention consists in a new and improved pulp-screening machine, which will be hereinafter fully described and claimed.

Referring to the accompanying drawings, Figure 1 is a perspective view of my new and improved pulp-screening machine, showing the hinged top opened. Fig. 2 is a longitudinal vertical central sectional view of the machine. Fig. 3 is a transverse vertical sectional view taken on the plane indicated by line $x-x$ of Fig. 2; and Fig. 4 is a detail view, hereinafter referred to.

The same numerals of reference indicate corresponding parts in all the figures.

Referring to the several parts by their designating numerals, 1 indicates the supporting-frame of the machine, and 2 indicates the rectangular body-frame, which has the series of parallel cross-bars 3, forming the rectangular spaces 4. At the top of the spaces 4 are secured the separate bellows-plates 5, the sides of which are connected to the cross-bars 3, while their ends are connected to the side pieces of the frame 2 by the flexible bellows-joints 6, of suitable material.

In the lower part of the frame 1 is mounted a longitudinal drive-shaft 7, which is revolved in any suitable manner, and upon this shaft, below the center of the bellows-plates, are mounted a series of eccentrics 8 9, which are connected to the middle underside of the bellows-plates by the frames 10. These eccentrics are arranged alternately, so that as the alternate eccentrics 8 elevate the alternate bellows-plates to which they are connected the other alternate eccentrics 9 will lower the alternate bellows-plates to which they are connected.

The outer edges of the flexible bellows-joints 6 are secured under metal strips 11 12. At the outer edge of the strips 11, which run around the top of frame 2, is secured a packing 13, of rubber or other suitable material, while the metal strips 12 extend along the

center of the top of the cross-bars 3, and along both their edges are secured packing-strips 14, of rubber or other suitable material.

55

15 indicates the top of the machine, which is hinged at one side, the screws at the lower leaf of each hinge passing through short slots in the hinge-leaf, or the top can be otherwise loosely hinged. The top has cross-bars 17, 60 which register with the cross-bars 3 of the body-frame 2, and the screen-plates 18 are secured on the top, as shown, with their side edges meeting on the cross-bars 17. The top 15 and body 2 have opposite apertured lugs 65 19, through which screw-bolts 20 pass, having nuts on their ends, and it will be seen that by tightening these screw-bolts the top will be locked tightly down, the top and its cross-bars pressing down firmly on the packing 13 70 and 14 around the ends and sides of the bellows-plates 5, thus separating each bellows-plate by an air-tight joint extending entirely around it and rendering each bellows and the screen-plate above it entirely independent 75 from all the others. This is an important feature of my invention.

The top of each bellows-plate is concave, and each bellows is formed with a central opening 21, from which a short pipe 22 leads 80 down into a box 23, which is secured longitudinally beneath the center of the cross-bars 3. The lower ends of these pipes 22 terminate at about the distance above the bottom of the box shown, and they are always 85 sealed by the water and paper "stuff" in the box, above which they never rise.

In operation it will be seen that as the drive-shaft 7 revolves the bellows-plates, each having its separate eccentric, will be moved 90 up and down alternately, as before described, the bellows-joints 6 permitting this movement, and, as the packing completely around each bellows separates it completely from the others when the top 15 is fastened down by 95 the screw-bolts, it will be seen that each bellows will operate independently of all the others and draw the paper-pulp which flows upon the screen-plate above it down through the screen-plate. The paper-pulp is thus 100 drawn down through the screen-plates upon the concave face of the independently-work-

ing bellows, and passes down through the central openings 21 and pipes 22 into the longitudinal box 23, from which it may be discharged through pipes 24, or in any other 5 suitable manner.

I do not wish to confine myself to the discharge-pipes here shown, as I may employ any other well-known means for effecting the same purpose.

10 It will be seen that by arranging the eccentric so that the bellows rise and fall alternately the machine will be steadied and will run evenly.

In order to brace and strengthen the comparatively-thin cross-bars 17 of the top, I employ brace-bolts 25, two to each bar, as shown, which pass up through the cross-bars 3 of the body 2 and through the bars 17, and have nuts 26 upon their upper threaded ends, 20 which fit in recesses in the bars 17, flush with the top of the same. When the top is closed and screwed down, the screw-bolts 25 are screwed up tight in the nuts 26, and will thus strengthen and brace the cross-bars 17 and 25 prevent springing of the screen-plates.

Having thus described my invention, what I claim, and desire to secure by Letters Patent, is—

1. In a pulp-screening machine, the combination of the series of separate screens 18, the series of independent bellows-plates 5, having the flexible bellows-joints 6 at their sides and ends, the drive-shaft 7, having the eccentrics 8 9 alternately arranged upon it, 30 and the connecting-frames 10, substantially as set forth.

2. The combination, in a pulp-screening machine, of the body-frame 2, having the parallel cross-bars 3, the series of independent reciprocating bellows-plates 5, having the flexible bellows-joints 6 at their sides and ends, the flexible packing-strips 13 and 14, extend- 40

ing around the ends and sides of each bellows, and the top 15, having the series of parallel cross-bars 17 and the screen-plates 18, substantially as set forth. 45

3. The combination of the body-frame having the cross-bars, the reciprocating bellows-plates having the bellows-joints and formed with the concave upper faces and central discharge-openings, the packing around each bellows, and the top having the cross-bars and the screen-plates, substantially as set forth. 50

4. The combination of the body-frame having the cross-bars, the reciprocating bellows-plates having the bellows-joints, the concave upper faces, the central discharge-openings, and the pipes leading down from said openings, the packing around said bellows, the top 60 having the cross-bars and the screen-plates, and the longitudinal box having the discharge, substantially as set forth. 55

5. The combination of the body-frame having the cross-bars, the reciprocating bellows-plates having the bellows-joints, the concave upper faces, the central openings and the pipes leading from said openings, the drive-shaft having the series of eccentrics alternately arranged upon it, the connecting- 65 frames, the packing around each bellows, the top having the cross-bars and screen-plates, and the longitudinal box having the discharge, substantially as set forth. 70

6. The combination, with the body having 75 the cross-bars formed with the apertures between the bellows, and the top having the apertured cross-bars which support the screen edges, of the brace-bolts having the nuts on their upper ends, substantially as set forth. 80
